UNITED STATES PATENT OFFICE.

ARTHUR PENTECOST, OF EAST ORANGE, NEW JERSEY, ASSIGNOR TO PIKE ADDING MACHINE COMPANY, OF EAST ORANGE, NEW JERSEY, A CORPORATION OF NEW JERSEY.

ATTACHMENT FOR ADDING-MACHINES.

No. 856,905.

Specification of Letters Patent.

Patented June 11, 1907.

Application filed September 6, 1905. Serial No. 277,194.

To all whom it may concern:

Be it known that I, ARTHUR PENTECOST, a subject of the King of Great Britain, residing at East Orange, in the county of Essex and State of New Jersey, have invented certain new and useful Improvements in Attachments for Adding-Machines, of which the following is a specification.

The present invention relates to an attachment for adding machines by means of which the operator will be notified of the completion of the recording of a predetermined number of items by the machine. Such an attachment is of considerable benefit in connection with calculations required to be expressed in a plurality of columns or tables of equal length or each containing the same number of items.

The object of the present invention is to provide an attachment for the purpose stated which will be operated from the recording mechanism of the machine, whereby it will accurately record or indicate the number of items listed and will be independent of and therefore permit variations in the paper feed or spacing between items if desired.

In the accompanying drawings,—Figure 1 is a side elevation of a portion of an adding machine having the present invention applied thereto; Fig. 2 is an elevation, partly in section, of a portion of the machine; Fig. 3 is a plan view; Fig. 4 is a longitudinal, vertical, sectional view, on the line 4—4 of Fig. 2. Fig. 5 is a longitudinal vertical sectional view through a portion of the machine in which the invention is illustrated as being embodied; and Fig. 6 is a plan view of a portion of the accumulating devices shown in Fig. 5.

While the invention is applicable to adding, or calculating machines of various forms, it is shown in the accompanying drawings as applied to a machine of the character invented by William H. Pike, Jr., and illustrated and described in Letters Patent Nos. 763,692 and 791,941, granted June 28, 1904 and June 6, 1905, respectively. As the present invention is not limited to use with such a machine, however, the latter has been illustrated more or less conventionally and only sufficiently to make clear the manner in which the attachment is applied to and oper-

ated by said machine. The machine referred to includes a recording mechanism comprising a platen 1, a plurality of type carriers 2 arranged side by side and each supporting a series of numeral type adapted to be moved toward the platen by suitable hammers 3, there being one of such hammers for each of the said type carriers. The positioning of the type carriers, or either of them, to bring the desired type thereon into position between the platen 1 and the co-operating hammer 3 is controlled by numeral keys 4 arranged in rows in a key board and the keys of each row controlling the action of one of the type carriers. By properly depressing the keys 4 representing the digits of a number to be recorded and actuating the machine, the type carriers corresponding to the numerical values represented by the rows of keys in which the depressed keys are situated will be caused to assume positions in which the type thereon corresponding to the depressed keys are brought into position beneath the hammers 3, and by the action of the latter, and a suitable inking device, the desired number will be recorded on a sheet or strip of paper supported by the platen.

Each type carrier is connected to a bar or strip 48 which is provided at its free end with a rack 49 adapted during its reciprocation in one direction, as hereinafter described, to engage and turn a pinion 50 connected with a numbered wheel 51 of the accumulating devices of the machine. The type carriers 2 and strips 48 connected therewith are moved in one direction through the action of a cam 52, mounted on the main power shaft of the machine, on a swinging frame including a bar or plate 53 extending transversely across the series of type carriers. Connected with each of the strips 48 is a spring 54 acting to move said strip and its connected type carrier in a direction opposite that in which they are moved by said cam 52. The extent of movement of each strip 48 and its type carrier 2, under the influence of the spring 54, is determined by the engagement of the depressed key 4, in the row corresponding to said strip, and a lateral projection or stud 55 on the strip.

Normally the accumulating wheels 51 are

held in such position that the pinions 50 thereof are out of engagement with the racks 49 and said wheels are moved to bring the pinions into engagement with the racks 5 upon the completion of the movement of the strips 48 under the influence of their springs 54, and when said strips are returned to their normal position by the action of the cam 52, the adding wheels 51 will be properly turned 10 to accumulate the amount represented by the depressed keys 4 and which amount has been recorded as above indicated.

The adding wheels are carried by a swinging frame one member 56 of which is connected to the lower end of a toggle 57 which is in turn connected by a link 58 with an arm 59 having a laterally projecting pin extending into the path of two shoulders on a swinging plate 60. By this means the link 20 58 is reciprocated and the toggle 57 adjusted to move the adding wheel pinions to and from the racks 49 at each operation of the machine as explained in detail in said Letters Patent.

25 It will be understood, by reference to the aforesaid patents, that the several type carriers 2 each corresponds to or represents a certain numerical value, and that the hammers 3 are so constructed and related that 30 whenever the machine is operated to effect an item record all of the hammers co-operating with type carriers representing values less than the highest value expressed by the depressed keys 4 will be operated. That is 35 at each operation of the recording mechanism the hammer co-operating with the type carrier representing the lowest numerical value will be operated. The said machine also includes two special keys 5, 6, the former 40 of which is operated when recording a "subtotal", and the latter being operated when a "total" is to be recorded.

Having thus briefly outlined the construction and operation of the recording and 45 accumulating mechanisms of the machine to which the attachment constituting the present invention is shown as applied in the accompanying drawing, said attachment will now be more particularly described.

50 Mounted on the casing 7 which incloses the recording mechanism of the machine is a base plate 8. From said plate rises a stud or post on which is supported a revoluble disk 9 having a toothed periphery. The disk 9 is 55 provided on its lower surface with a spring barrel or casing 10 within which is arranged a coiled spring, one end of said spring being secured to the post about which the disk 9 rotates and the other end being adapted to 60 contact with an inwardly extending projection on the spring barrel 10. Preferably the spring barrel is provided with an inwardly extending projection 11, which, as shown in Fig. 3 has oppositely beveled faces 65 and the outer end of the spring is provided

with an enlarged portion 12 having similarly inclined faces, whereby, when the spring has been placed under the maximum tension desired, a further rotation of the disk 9 and the barrel 10 will not break or otherwise damage 70 the spring.

An arm 13 is mounted on the post supporting the toothed disk 9, said arm being supported independently of the disk and having at its outer end a pawl 14 adapted to engage 75 the teeth on the periphery of the disk. A coiled spring 15 acts to normally draw the arm 13 against a pin 16 rising from the base plate 8. Motion is imparted to the arm 13 by a finger 17 rising from the hammer 3 co-operating with the type carrier corresponding to the lowest numerical value in the recording mechanism. As said hammer is released, which as before described occurs whenever the recording mechanism is operated to print an item, the arm 17 will contact with the arm 13 and through the engagement of the dog or pawl 14 move the toothed disk 9 one step in the direction of the arrow x. The disk 9 is held in the position to which it is 80 turned by such movement of the arm 13 by a retaining dog or lock pawl 18.

Means are provided whereby after a predetermined number of items have been listed, or the recording mechanism has been actuated a certain number of times, at each of which movements the disk 9 has been moved, as described, one step, an audible signal will be automatically produced. As shown this signal mechanism comprises a gong or bell 19 85 suitably supported on the casing of the machine and provided with a hammer or clapper 20 with which is connected a finger 21, the free end of which extends upwardly above the plane of the disk 9 into the path of an arm 105 22 adjustably mounted above said disk. The arm 22 may be mounted in any suitable manner. As shown it is supported to turn about the axis of the disk and provided on its lower face with a pin or stud adapted to enter either 110 of a series of sockets 23 formed in the disk 9 and corresponding in number and location to the peripheral teeth of said disk. Preferably the disk is provided with 100 teeth and adjacent the sockets 23 is arranged a series of numerals each being adjacent one of said sockets and indicating the relative position of such socket and the corresponding tooth in the series. The arm 22 is also provided with a pointer 24 which is of such length as to 115 travel over the series of numbers on the disk 9 and to indicate with which socket 23 said arm is engaged. When the parts are in normal position the arm 13 is held against the pin 16 by its spring 15 and a lever 25 carried 120 by the disk 9 engages two pins 26, 27 respectively secured to the disk and base plate 8.

If it is desired to have the signal bell 9 sounded after the recording mechanism has been operated twenty-five times, for example, 130

the indicating arm 22, which is preferably made of resilient material, is adjusted so as to engage the socket 23 designated by the numeral 25, which, as above described, is separated from the zero or starting position of the disk by a distance equal to twenty-five of the peripheral teeth on the disk. At each operation of the recording mechanism the arm 17 will move the arm 13 and feed the disk one tooth, said arm and its pawl 14 returning to their normal position under the influence of the spring 15 when the hammers 3 of the recording mechanism are restored to their elevated positions; and the disk 9 is held from movement under the influence of its power spring, between operations of the recording mechanism, by the holding pawl 18. By such movement of the disk 9 the arm 22 connected therewith is brought into engagement with the finger 21 of the bell hammer 20, and, in the example assumed, as the twenty-fifth step by step movement of the disk is completed said arm 22 will pass from engagement with the finger 21 and the hammer 20 being thus released will be forced against the bell 19 by its spring thus notifying the operator that the desired number of items has been recorded by the machine. To provide for readily disengaging the arm 22 from the disk 9 and adjusting it relative to said disk it is provided with a suitable finger piece 22a.

Before the machine is operated to record a second series of items it is necessary that the disk 9 and parts connected therewith be returned to their normal positions. This return movement is effected through the power of the spring contained in the barrel 10, which has been placed under tension by the previous step by step movement of the disk; and in order to allow said spring to actuate the disk it is necessary that both the holding and feeding pawls be disengaged therefrom. Preferably the feeding pawl is normally held from engagement with the teeth of the disk 9 by a pin 28 on the base plate 1, said pin being so arranged that the curved inner face of the pawl 14 bears thereon and when the arm 13 is in contact with the stop 16, the point or free end of said pawl 15 is clear of the disk 9. To withdraw the holding dog 18 means operated by either the "sub-total" or "total" keys, 5, 6, of the adding machine are employed. These means include a pivotally mounted release arm 29, the free end of which is adapted to engage the pawl 18 and the other end of which is connected by suitable links and levers with the said "sub-total" and "total" keys.

As shown the shaft on which the release arm 29 is mounted has an arm 35 connected by a link 36 with an arm of a bell-crank 37, the other arm of which is connected through a link 38 with an arm 39 on a shaft 40 mounted in suitable bearings on the base of the machine. Said shaft 40 is also provided with

an arm 41 which is connected by links 42 and 43 with a rocking plate 44 adapted to control the engagement and disengagement of the accumulating devices with the type carriers in the proper manner to record either a total or a sub-total, as described in detail in the aforesaid patent No. 763,692. The said link 43 is connected with a lever 45 and the sub-total and total keys 5, 6, are respectively provided with pins 46 and 47 adapted to operate said lever in the manner described in said patent. Therefore whenever either the "sub-total" or "total" key is depressed the detaining dog 18 will be moved from engagement with the disk 9, which, together with its engaged arm 22, will be returned to normal position by its power spring. The finger 21 of the signal mechanism is pivotally mounted so that it will yield and offer no obstruction to this return or restoring movement of the arm 22.

An important advantage attained by employing the "sub-total" and "total" keys to operate the release mechanism is that either of said keys, when operated, is held in its depressed position until a full cycle of movement of the machine is completed, as explained in the aforesaid patent No. 763,692, there will be sufficient time for the disk 9 to come to rest, even after any slight rebound due to the sudden contact of the lever 25 with the pins 26, 27, before the pawl 18 engages the disk.

The attachment is also preferably provided with a stationary pointer 30, which, when the disk 9 is in its normal or starting position, alines with the socket 23 designated by the character zero on said disk. This pointer 30 therefore serves to indicate at any time the number of steps of movement which have been imparted to the disk 9 by the arm 13, or the number of items which have been listed by the recording mechanism.

The operation of the invention will be readily understood from the foregoing description in connection with the drawings, and the advantages thereof appreciated. By actuating the indicating disk from the recording mechanism there is no possibility of including more or less than the desired number of items in any column and the disk is always returned to its zero position when either a sub-total or total of the previously listed items is recorded. It is possible to thus obtain an accurate division of a given number of items regardless of the space or distance separating successive items. In other words, by operating the indicating attachment independently of the paper feeding mechanism the latter may be adjusted to provide any desired distance between items.

It will be noted that the stationary pointer 30 in connection with the toothed and numbered disk 9 forms an accurate register of the number of operations of the recording mech-

anism and that by the operation of either the "sub-total" or "total" keys the disk is returned to the normal or zero position. Therefore an operator can, without employing the indicating arm 22, or independently thereof, instantly determine the number of operations of the recording mechanism which have occurred since the last "sub-total" or "total" was recorded. And as by operating either special key 5 or 6 the parts are returned to normal position it is possible to provide columns of uniform length.

Means are also provided whereby the attachment may be rendered inoperative at the will of the party using the machine. As shown these means include a lever 31 which is suitably fulcrumed on the base plate 8 and has one end projecting beyond the periphery of disk 9 to form a handle by which it may be moved about its pivot. At the other end said lever is provided with an upward extension 32 adapted to bear against one edge of the arm 13 by which the disk 9 is moved. When the lever 31 is in the position shown in Fig. 3 the arm 13 is held against its stop 16 and in the path of movement of the finger 17, whereby at each movement of the latter the arm is rocked and the disk 9 moved step by step as before described. By turning the lever 31 on its pivot however the extension 32 thereon will be brought against the arm 13 and the latter will be moved to a position beyond the path of movement of the finger 17. By this means the attachment can be rendered inoperative or brought into action at the pleasure of the operator.

The lever 31 is provided with a projection 33, extending concentric with its pivot and having formed therein two apertures adapted to engage a pin or stud rising from the base plate 8 and to securely hold the lever in either of its two positions. Said lever being of thin material forms a spring blade and is adapted to engage the said retaining stud with a snap action.

It is of course desirable that the arm 22 which actuates the audible signal should be so engaged with the disk 9 at each adjustment as to uniformly actuate the bell hammer. For this reason the stationary indicator or pointer 30 is provided with a depending pin 34 the free end of which will bear on the upper surface of the arm 22 as the latter passes beneath it and thus cause said arm to always occupy the same elevation at the time of its engagement with the finger 21 of the bell hammer. To prevent the pin 34 from offering any obstruction to the movement of the arm 22 the upper surface of said arm is beveled, or reduced in thickness toward both edges from its central line.

I am aware that it has been heretofore proposed to provide adding machines with attachments intended or designed to accomplish the results attained by my invention

but each of the constructions heretofore proposed or employed, so far as known to me, is objectionable and ineffective. The devices referred to are operated from or by the paper feeding means and therefore the register or counter is actuated whenever a feed movement is imparted to the paper, whether or not such movement is simultaneous with the accumulating of an item by the adding mechanism or the recording of such an item on the paper. That is, the devices heretofore proposed do not accurately record the number of items accumulated or listed by the machine but merely indicate the successive feed movements of the paper which may, but do not necessarily, correspond with the number of items accumulated and recorded.

By my invention, as hereinbefore described, the movable member of the counter or register is only actuated when the printing hammer corresponding to the lowest denomination is operated in recording an item accumulated and therefore the step by step movements of the counter or register are directly controlled by the accumulating devices. In other words, the actuation of the register is entirely independent of the paper feeding devices and the operation of the latter may be varied to change the spacing between items as desired without in the least affecting the operation of the register which accurately records only the items accumulated.

Having described my invention, what I claim is:

1. The combination with the recording mechanism of an adding machine including a series of type and means for operating them, of a signal device adapted to be automatically actuated upon and only on the completion of a predetermined number of operations of the recording mechanism.

2. The combination with the recording mechanism of an adding machine including a series of type and means for operating them, of an indicating device adapted to be actuated by the type operating devices of the recording mechanism.

3. The combination with the recording mechanism of an adding machine including a series of type and means for operating them, of means for producing an audible signal upon and only on the completion of a predetermined number of movements of the type operating devices of the recording mechanism.

4. The combination with a recording mechanism including a series of type and a hammer for operating them, of a signal device adapted to be actuated upon the completion of a predetermined number of operations of said hammer.

5. The combination with a recording mechanism including a plurality of series of

type and an independent device for co-operating with each of said series, of an indicating device adapted to be actuated by one of said type operating devices of the recording mechanism.

6. The combination with a recording mechanism including a plurality of series of type and a hammer for co-operating with each of said series, of an indicating device adapted to be actuated by one of said hammers, and a signal mechanism adapted to be operated upon and only on the completion of a predetermined number of movements of the said hammer.

15 7. The combination with a recording mechanism including a plurality of type carriers, a series of type mounted in each carrier, and means for operating said type, of a signal device adapted to be automatically operated upon and only on the completion of a predetermined number of operations of the recording mechanism.

25 8. The combination with a recording mechanism including a plurality of series of type and a hammer for co-operating with each of said series, of an audible signal device, and means for operating said signal device adapted to be actuated by one of said hammers of the recording mechanism.

30 9. The combination with a recording mechanism including a plurality of series of type and a hammer for co-operating with each of said series, of means for producing an audible signal when one of said hammers has been operated a predetermined number of times.

40 10. The combination with a recording mechanism including a plurality of series of type and a hammer for co-operating with each of said series, of means for indicating when one of said hammers has completed a predetermined number of strokes.

45 11. The combination with a recording mechanism including a plurality of series of type, each series corresponding to a certain numerical value and devices for operating said type, of means for indicating when the series of type corresponding to the lowest numerical value has been operated a predetermined number of times.

50 12. The combination with a recording mechanism including a plurality of series of type, each series corresponding to a certain numerical value and a hammer for co-operating with each of said series of type, of means for indicating when the hammer co-operating with the series of type representing the lowest numerical value has been operated a predetermined number of times.

60 13. The combination with the recording mechanism of an adding machine, of a signal mechanism adapted to indicate the completion of a predetermined number of operations of said recording mechanism and including

at each actuation of said recording mechanism, and means for returning said adjustable member to its original position when the recording mechanism is operated to record the sum of the amounts represented by the previous operations of said mechanism.

14. The combination with the recording mechanism of an adding machine adapted to be controlled by a plurality of rows of keys and having a special device adapted to be operated when the total of a series of items is to be recorded, of a signal mechanism adapted to indicate the completion of a predetermined number of operations of said recording means, including an adjustable member movable step by step at each actuation of said recording mechanism, and means controlled by said total taking devices for returning said adjustable member to its original position.

15. The combination with the recording mechanism of an adding machine, a plurality of number keys, a "sub-total" key, and a "total" key, of a signal mechanism adapted to indicate the completion of a predetermined number of operations of said recording mechanism and including an adjustable member movable step by step at each actuation of said recording mechanism and means controlled by either the "sub-total" or "total" key for returning the said adjustable member to its original position when the recording mechanism is operated to record the sum of the amounts represented by the previous operations of said mechanism.

16. The combination with a recording mechanism including a series of type and means for operating them, of a register or counter including a relatively stationary member and a member movable step by step past said stationary member at each actuation of the recording mechanism, and means for returning said movable part to its normal position whenever the recording mechanism is actuated to record the sum of the items recorded by previous actuations of said mechanism.

17. The combination with the accumulating devices and the recording mechanism of an adding machine, of an item counter or register adapted to be operated at each actuation of said recording mechanism, and means for returning the counter or register to zero position whenever the sum of a series of items is recorded by the recording mechanism.

18. The combination with the recording mechanism of an adding machine and with "total" and "sub-total" keys adapted to control the actuation of the recording mechanism, of a counter or register adapted to be actuated at each operation of the recording mechanism to indicate the number of items recorded, and connections between said register and the "sub-total" and "total" keys, whereby when either of said keys is actuated

to cause the recording of the sum of the items previously recorded the register will be returned to normal, or zero position.

19. The combination with the recording mechanism of an adding machine, and an indicating device adapted to be operated at each actuation of the recording mechanism, of means for adjusting a member of said indicating device to prevent actuation thereof by the recording mechanism.

20. The combination with the recording mechanism of an adding machine, of an indicator device having an operating arm adapted to be moved by the said recording mechanism, and means for adjusting said arm to prevent its operation by said recording mechanism.

21. The combination with the accumulating devices of an adding machine, of a counter or register adapted to be actuated whenever and only when an item is accumulated.

22. The combination with the accumulating devices of an adding machine, of a counter or register adapted to be actuated step by step as items are accumulated, and a signal

device adapted to be automatically operated upon and only on the completion of the accumulation of a predetermined number of items.

23. The combination with the accumulating devices of an adding machine, of a register or counter including a relatively stationary member and a member movable step by step past said stationary member whenever and only when an item is accumulated.

24. The combination with the accumulating devices of an adding machine, of a register or counter including a relatively stationary member and a member movable step by step past said stationary member whenever and only when an item is accumulated, and means for returning said movable part to its normal position whenever the sum of the items is recorded.

In testimony whereof I affix my signature in presence of two witnesses.

ARTHUR PENTECOST.
